G. T. BUCKHAM.
MOUNTING OF AUTOMATIC GUNS.
APPLICATION FILED JUNE 21, 1917.

1,303,023.

Patented May 6, 1919.

FIG. 1

FIG. 2

Inventor:
George T. Buckham
By *James A. Martin* (Signature)
Attala, Mississippi, U.S.A.

UNITED STATES PATENT OFFICE.

GEORGE THOMAS BUCKHAM, OF WESTMINSTER, LONDON, ENGLAND, ASSIGNOR TO
VICKERS LIMITED, OF WESTMINSTER, ENGLAND.

MOUNTING OF AUTOMATIC GUNS.

1,303,023.

Specification of Letters Patent.

Patented May 6, 1919.

Application filed June 21, 1917. Serial No. 176,116.

To all whom it may concern:

Be it known that I, GEORGE THOMAS BUCKHAM, a subject of the King of Great Britain, residing at Vickers House, Broad-
5 way, Westminster, in the county of London, England, have invented certain new and useful Improvements in or Relating to the Mountings of Automatic Guns, of which the following is a specification.

10 This invention relates to the mountings of automatic guns.

According to the invention the gun, in order to enable its height to be varied while the mounting itself occupies a fixed position, is connected to the crosshead by means of a movable support comprising two arms or links, the upper ends of which are pivotally connected to suitable parts of the gun and their lower ends are pivotally connected 15 to a base member or bracket which is pivoted at its forward end to the crosshead of the gun and connected at its rear end to the usual elevating gear carried by the usual rearward extension of the crosshead.
20 A suitable device is provided for holding the arms at any desired angle in relation to the base member or bracket.

In order that the invention may be clearly understood and readily carried into effect 30 the same will be described more fully with reference to the accompanying drawings in which:—

Figures 1 and 2 are side elevations of a tripod gun mounting constructed in accordance with the invention; these figures showing the gun in its fully raised and lowered positions respectively.

A is the training socket of the mounting and A' is the crosshead having the usual rearward extension a' that carries the elevating gear a. B is the gun. B', B² are the two arms or links that constitute the aforesaid movable support for the gun and B³ is the base member or bracket between 45 which and the gun the said arms are arranged.

In the example shown the forward end of the bracket B³ is disposed between the side cheeks of the crosshead and is pivotally connected thereto by a pin b³ passed through a hole in the base member and through the hole in the crosshead side cheeks that usually receives the trunnion pin. The rear end of the bracket has a lug (or lugs) b² adapted 50 to receive a pin b' which passes through the

upper end of the screw of the elevating gear a, as is usual in gun mountings of this character. The front arm B' is pivotally connected at its upper end to the trunnion bracket of the gun by a pin b and at its lower end to the base member B³ by the above-mentioned pin b³. The rear arm B² is pivotally connected at its lower end by a suitable pin to the base member B³ and at its upper end by a pin b^x to the usual 60 elevating lug or lugs on the mechanism casting of the gun. The aforesaid device for holding the arms B', B² rigid comprises, in the example shown, a rod C which is pivotally connected at c to the front arm B' near 70 the upper end thereof and extends rearwardly and downwardly to a sleeve C' through which the rod passes; this sleeve is pivoted on the pin that connects the rear arm B² to the base member B³ and is provided with a clamp which is operated by a handle c' and which, by engaging with the rod C, serves to hold it and therefore the arms B', B² in the adjusted position with 75 the gun at the desired height. When the elevating gear a is operated to adjust the gun for range, the base member B³ is rocked about the pin b³. It will be understood that the arms B', B², the base member B³ and the rod C constitute a self-contained unit 80 which can be readily interposed between the mounting and the gun so that the existing mountings can be readily converted. It will also be understood that the base member B³ is constructed to suit the particular 85 type of tripod or pedestal mounting to which it is to be attached.

It will be seen that in the example shown the gun is lowered by moving it rearward; it is however to be understood that the arrangement might be so modified that the lowering of the gun would be effected by moving it in a forward direction. In this case the rod C might be arranged between the arm B² and the pin b³ which would 90 then carry the sleeve C'.
95

What I claim and desire to secure by Letters Patent of the United States is:—

1. In a mounting for an automatic gun, the combination of a crosshead, an elevating gear, a support comprising a base member or bracket pivoted to the crosshead and connected to the elevating gear, a pair of parallel-motion arms or links pivotally connected at opposite ends to the base member 105 110

and to the gun, and connecting means between one arm and the base member for rigidly holding said arms in adjusted angular position with relation to the base member; substantially as described.

2. In a mounting for an automatic gun, the combination of a crosshead, an elevating gear, a support comprising a base member or bracket pivoted to the crosshead and connected to the elevating gear and two parallel motion arms or links arranged between the gun and the said base member, and means for rigidly holding said

arms in any adjusted position, said holding means comprising a rod pivoted to one of the arms near the upper end thereof, a swiveling block through which the rod passes carried by the pivot pin connecting the other arm to the base member and a clamp provided on said block to engage the said rod.

In testimony whereof I affix my signature in the presence of two witnesses.

GEORGE THOMAS BUCKHAM
